UNITED STATES PATENT OFFICE.

IGNATZ WEISNEK, OF FEDERAL, PENNSYLVANIA, ASSIGNOR OF ONE-HALF TO JOSEPHINE EVANS, OF FEDERAL, PENNSYLVANIA.

LOCK-COVER.

SPECIFICATION forming part of Letters Patent No. 760,830, dated May 24, 1904.

Application filed October 2, 1903. Serial No. 176,535. (No model.)

To all whom it may concern:

Be it known that I, IGNATZ WEISNEK, a citizen of the United States of America, residing at Federal, in the county of Allegheny and State of Pennsylvania, have invented certain new and useful Improvements in Lock-Covers, of which the following is a specification, reference being had therein to the accompanying drawings.

10 This invention relates to certain new and useful improvements in locks, and relates more specifically to a cover and auxiliary lock for the main lock.

The device is particularly adapted to be used in connection with trunks, chests, and other like devices, though it may be employed in other connections for which it may be found applicable.

15 The invention consists in the novel construction, combination, and arrangement of parts to be hereinafter more fully described, and specifically pointed out in the claim.

20 In describing the invention in detail reference is had to the accompanying drawings, forming a part of this specification, and wherein like numerals of reference indicate like parts throughout the several views, in which—

25 Figure 1 is a front elevation of a trunk equipped with my improved lock-cover, the latter being in the closed or locked position. Fig. 2 is a front elevation of a part of the trunk, showing the lock-cover in the open position. Fig. 3 is a detached detail perspective view of the hasp of the main lock. Fig. 4 is a transverse vertical sectional view of the main lock. Fig. 5 is a detached detail perspective view of the lock-cover, and Fig. 6 is a like view of the keeper to receive the lock-bolt and the lock carried by the lock-cover.

30 In the accompanying drawings, 1 indicates the main lock, which in the present illustration I have shown as being of the combination-lock type, employing, in connection with the tumblers, a hasp the bolt 2 of which is hinged to the securing-plate 3 and carries the rod 4, provided with a plurality of lugs 5, between which the tumblers of the combination-

lock are received. This combination-lock is suitably positioned in the front wall of the 50 trunk, chest, or other article, with the dial on the outer face thereof, and to prevent manipulation of this dial by unauthorized persons I provide the flanged cover 6, having a hinge 7 secured to one end of said flange, on the exterior thereof, and to the front plate 8 of the combination-lock. Hinge 6 is preferably of a length equal to the width of cover 6, extending the length of one end flange of said cover for the purpose of strengthening the 55 connection between the hinge and the cover and the plate 8. In this cover-flange is arranged a lock 9 of the key type, the lock-bolt 10 of which is adapted to be actuated by the key inserted through the keyhole 11 in the 60 front of the cover to engage or disengage the lock-bolt with opening 12, formed on the outwardly-extending portion of keeper 14, which is secured on the face-plate 8 of the combination-lock. When the cover 6 is in the closed 65 position, the lock-bolt 10 of the lock 9 is thrown into engagement with opening 12 and the cover will be held in the closed position, access to the dial of the combination-lock being prevented. The cover 6 may, if desired, 70 be hinged direct to the outer face of the trunk or chest, though it is preferable to provide the face-plate 8 for this form of lock, and this employment of said plate affords better securing means for the cover and keeper of the 75 auxiliary lock.

80 It will be obvious that various changes may be made in the details of construction without departing from the general spirit of my invention.

85 Having fully described my invention, what I claim as new, and desire to secure by Letters Patent, is—

In combination with the plate of a lock, a lock-cover in its entirety comprising three 90 parts, a rectangular member having its side and end walls formed with flanges, a hinge of the same length as the width of said member having one of its leaves secured to the exterior of one end flange and its other leaf 95 secured to said plate, a key-operated lock se-

cured to the interior of said member and abutting the opposite end flange and the adjacent side flange thereof, and a single keeper having an outwardly-extending apertured portion to align with the lock-bolt of the lock, said member having a keyhole formed therein to enable access to said key-operated lock.

In testimony whereof I affix my signature in the presence of two witnesses.

IGNATZ WEISNEK.
